UNITED STATES PATENT OFFICE.

GEORGE C. SAVAGE, OF LYNCHBURG, VIRGINIA.

ATTACHMENT FOR EYEGLASS-CASES.

1,199,618.

Specification of Letters Patent. Patented Sept. 26, 1916.

Application filed April 12, 1916. Serial No. 90,743.

To all whom it may concern:

Be it known that I, GEORGE C. SAVAGE, a citizen of the United States, residing at Lynchburg, in the county of Campbell, State of Virginia, have invented certain new and useful Improvements in Attachments for Eyeglass-Cases; and I do hereby declare the following to be a full, clear, and exact description of the invention, such as will enable others skilled in the art to which it appertains to make and use the same.

The present invention is directed to improvements in combined eye glass case and pencil holder, and has for its object to provide a device of this character constructed in such a manner that a pencil can be attached to the case so as to prevent the loss of the pencil, the pencil holding means being so arranged that it will in no way interfere.

A further object of the invention is to provide a device of this character so constructed that the pencil holder serves for yieldably holding the cover of the case in its closed position.

With these and other objects in view, this invention resides in the novel features of construction, formation, combination and arrangement of parts to be hereinafter more fully described, claimed and illustrated in the accompanying drawing, in which:—

Figure 1 is a plan view of the device. Fig. 2 is an end view. Fig. 3 is a sectional view of line 3—3 of Fig. 1. Fig. 4 is a bottom plan view.

Referring to the drawing 1 indicates the eye glass case, which is preferably formed

from light sheet metal and has secured in any suitable manner to its bottom 2 a plate 3, the outer edge of which being bent to provide a pencil holding sleeve 4, the longitudinal edge 5 thereof terminates in an angular disposed flange 6.

The cover 7 of the case 1 has its rear edge riveted to the flange 6, and since said flange, as well as the holder 4 is resilient it is obvious that the cover 7 will be held in engagement with the top 8 of the case.

From the foregoing description it will be seen that a pencil can be readily engaged in the holder 4 and that the cover 7 can be opened and closed without interfering with the holder. It will be further noted that the holder 4 is so constructed that it not only constitutes a holder for a pencil but also serves as means for connecting the cover. 55

What is claimed is:

In a device of the class described, the combination of an eye glass case having a plate secured to its bottom, a sleeve carried by one end of the plate, said sleeve having its longitudinal edge provided with a flange, a cover for the case, said cover being secured to said flange, said sleeve being adapted to receive a pencil and being formed from resilient metal, whereby the cover is held in yielding engagement with the case. 65

In testimony whereof, I affix my signature, in the presence of two witnesses.

GEORGE C. SAVAGE.

Witnesses:

J. J. DITCH,
H. L. WILKINS.
